John Ellis

UNITED STATES PATENT OFFICE.

NORMAN C. NICOL, OF BUFFALO, NEW YORK.

HINGE.

1,313,726.

Specification of Letters Patent. Patented Aug. 19, 1919.

Application filed March 8, 1918. Serial No. 221,103.

To all whom it may concern:

Be it known that I, NORMAN C. NICOL, a citizen of the United States of America, and a resident of the city of Buffalo, county of Erie, and State of New York, have invented certain new and useful Improvements in Hinges, of which the following is a full, clear, and exact description.

My invention relates generally to hinges and more particularly to hinges of the concealed type, and which may be used on doors, gates, window sash, piano covers, wardrobes, closets, and for various kinds of cabinet work.

15 The principal object of my invention has been to provide a hinge which shall be simple in its operation and very compact in its design, so that it may be attached to comparatively thin materials.

20 Another object has been to provide a hinge, the construction and operation of which is such as to prevent the movable member, to which it is attached, when in its closed position, from moving away from 25 the stationary frame or support to which it is pivotally attached.

A further object has been to provide a device which shall have such a radius of movement as to give the movable member 30 the desired amount of "throw", whereby rubbing of the parts is prevented during the operation of the hinge, and whereby the same is made adaptable for different thicknesses of material.

35 The above objects and advantages have been accomplished by the device shown in the accompanying drawings. In the drawings:

40 Figure 1 is a front view of my hinge in its open position.

Fig. 2 is a sectional elevation of my device and is taken on line 2—2 of Fig. 1, with the hinge members in their closed position.

45 Fig. 3 is a front elevation of my hinge, showing the relation of parts when the same is partially closed.

50 Fig. 4 is a sectional elevation taken on line 4—4 of Fig. 2, showing the inner face of one of the hinge leaves.

Fig. 5 is a transverse sectional elevation taken on line 5—5 of Fig. 1.

Fig. 6 is a front elevation of a modified form of hinge.

55 Fig. 7 is a longitudinal, sectional elevation of another modified form of hinge.

Referring now to the drawings, and particularly to Figs. 1 to 5, inclusive, 10 are the casings of my hinge, which are preferably made of sheet metal and formed in the shape of a box, as shown. 11 may represent the stationary member and 12 the movable member, to which my hinge is attached; the casings being let into the edges of these members and set in flush with the face thereof. The usual screws 13 serve to retain the casings in position.

The butts are connected by a supplemental hinge comprising leaves 15 and 16. These leaves are pivotally united at their inner ends 17 by a pin 18, whose axis lies midway between the casings, when in their open position and parallel to the faces of the side walls thereof. The end 17 of preferably the leaf 15 is provided with a lip 19 which contacts with the upper surface of the end 17 of the leaf 16 when the parts are in their open position, as shown in Fig. 5, so that the ends are prevented from opening through an angle greater than 180°. By this arrangement, the leaves close readily and binding thereof is prevented. The outer end of each of the leaves 15 and 16 is pivotally united with one of the casings 10 by means of a pivot pin 20. These pins are oppositely arranged, each at an angle of 45° to the face of either of the side walls of the casings and they are supported within the casings 10 by means of a lug 21, formed preferably by bending a portion of the end wall of the casing, and by an indented portion 22, formed preferably from one of the side walls of each of the casings. The outer ends of each of the leaves is provided with a tab 23 and a tab 24, which are bent at substantially right angles to the face of the leaves and are pivotally attached to the pivot pins 20.

It will be seen, by reference to Fig. 2, that the two leaves 15 and 16 do not fully close when the hinge is in its closed position; and, because of the angular relation of the pivot pins 20 and the pin 18, the distance between the corners of the leaves at which the lugs 23 are located will be greater than the distance between the corners at which the lugs 24 are located. To compensate for this difference in distance, without having to warp the leaves 15 and 16, the lugs 23 are made longer than the lugs 24, and the pins 20 are sloped at an angle with the outer faces of the casings, as clearly shown

in Figs. 2 and 4. In order to make the leaves 15 and 16 of light material and yet of sufficient strength, the edges are preferably bent up at right angles to the face of 5 the leaf, as clearly shown in the drawings.

Each of the casings is provided with a closure plate 25, which is pivoted within the casing at the end opposite the pivotal connection of the leaves and which is arranged 10 to close the openings within the casings when the hinge is in its open position, as shown in Fig. 1. These plates are mounted upon pivot pins 26 and are elevated to the position shown in Fig. 1, by means of a 15 spring 33, arranged beneath each plate. The plates are maintained in the position shown in Fig. 1, by any suitable means, but preferably a tab 27, formed from the side wall of the casing and bent over at right angles 20 so as to act as a stop for the outward movement of the plate.

In Fig. 6, I show a modification of my hinge, where the outer ends of the leaves 28 are pivotally united to the casings 29 at 25 angles of substantially 30° with the side wall of either of the casings 29. One of the leaves 28 is shown in its closed position by the dotted lines in the left hand casing of Fig. 6. This view shows that the pivot 30 pins at the outer ends of the hinge leaves need not necessarily be arranged at an angle of 45° with the side walls of the casings, but that this angle may be made 30° or varied to any other suitable angle.

35 In Fig. 7, where I show another modified form of my invention, all the pivotal pins have their axes arranged in parallel planes. Thus the pivotal pins 31 for the outer ends of the leaves are arranged parallel to each 40 other when completely closed or open and each always parallel to the central pivotal pin 32, instead of being arranged at an angle thereto, as is the case in the form shown in Figs. 1 to 5, inclusive. To compensate for 45 the difference in the distance between the opposite corners of the outer ends of these leaves, as described above, the leaves in this form of the invention are warped or twisted, as shown in this figure.

50 From the foregoing, it will be seen that my hinge is very compact in its design and requires the use of a comparatively few parts, thus making it very durable and not liable to get out of order. As shown in Fig. 55 3, my hinge when opening separates the parts to which it is attached, so that they have reached nearly the maximum separation when opened to an angle of 90° . Moreover the connections of all the parts in my 60 hinge are pivotal, thus doing away with all sliding connections and the resulting friction.

From the foregoing, it will be seen that the leaves of the supplemental hinge are so 65 mounted that when the casings are moved

toward or from each other, the central pivot of the supplemental hinge leaves will move through a plane which is at right angles with the plane of rotation of the casings and assume constantly different angular relations with the casings. 70

While I have shown and described the leaves of my supplemental hinge as having an angular connection with the casings of substantially 45° and 30° , it is obvious that the parts may have any desired angular relation. Furthermore, if desired, the closure plate 25 may be omitted, and the pivot pins for the inner ends of the leaves may be arranged in parallel planes or in planes at an angle to each other. Owing to the construction of my invention, it is preferably advisable, in order to secure the required stability, to use more than one supplemental hinge. It will be clearly understood, however, from the foregoing description that when a plurality of supplemental hinges is employed, it will be a duplication of the single structure herein shown and described. These and other modifications of the details herein shown and described may be made without departing from the spirit of my invention or the scope of the appended claims, and I do not, therefore, wish to be limited to the exact embodiment herein shown and described. 80 90 95

Having thus described my invention, what I claim is:

1. A hinge comprising box-shaped casings, a two-leaf supplemental hinge provided with a central pivot, and a pivot pin for the outer end of each leaf of the supplemental hinge, each pin being mounted in the casings and angularly arranged with respect to the faces of the side walls of the casings as well as to the top faces of the casings. 100 105

2. A hinge comprising box-shaped casings, a two-leaf supplemental hinge provided with a central pivot, a pivot pin for the outer end of each leaf of the supplemental hinge, each pin being mounted in the casings and angularly arranged with respect to the faces of the side walls of the casings, and means for preventing the supplemental hinge members from opening through an angle greater than 180° . 110 115

3. A hinge comprising box-shaped casings, a two-leaf supplemental hinge provided with a central pivot, a stop carried by one of the leaves of said supplemental hinge and arranged to engage the other leaf of said hinge, a pivot pin for the outer end of each leaf of the supplemental hinge, each pin being mounted in the casings, and means, formed from the side walls of the casings, for supporting the pivot pins. 120 125

4. A hinge comprising box-shaped casings, a two-leaf supplemental hinge provided with a central pivot and a pivot pin 130

for the outer end of each leaf of the supplemental hinge, each pin being mounted in the casings and angularly arranged with respect to the faces of the side walls of the casings, and a closure plate disposed within each of the casings arranged to close the opening of each of the casings when the hinge is in its open position.

5. A hinge comprising box-shaped casings, a two-leaf supplemental hinge provided with a central pivot, a pivot pin for the outer end of each leaf of the supplemental hinge, each pin being mounted in the casings and angularly arranged with respect to the faces of the side walls of the casings, and a closure plate pivoted within

each of the casings and arranged to close the opening within the casings when the hinge is in its open position.

6. A hinge means comprising a plurality of box-shaped casings, and a plurality of supplemental hinges, each supplemental hinge comprising two leaves having a common central pivot, and pivot pins for the outer ends of each of the supplemental hinges, the last mentioned pins being mounted in the casings and angularly arranged with respect to the top faces of the casings, as well as the faces of the side walls thereof.

10 In testimony whereof, I have hereunto signed my name.

NORMAN C. NICOL.
